US00D919804S

(12) **United States Design Patent** (10) **Patent No.:** **US D919,804 S**
(45) **Date of Patent:** **** May 18, 2021**

(54) **HANDLE FOR MEDICAL DELIVERY APPARATUS DEVICE**

(71) Applicant: **W. L. Gore & Associates, Inc.**, Newark, DE (US)

(72) Inventors: **Daniel S. Cole**, Flagstaff, AZ (US); **Jeremy J. Odegard**, River Falls, WI (US); **Gerald A. Thoe**, New Richmond, WI (US); **Elizabeth R. Volk**, St. Paul, MN (US)

(73) Assignee: **W. L. Gore & Associates, Inc.**, Newark, DE (US)

(**) Term: **15 Years**

(21) Appl. No.: **29/573,589**

(22) Filed: **Aug. 8, 2016**

Related U.S. Application Data

(63) Continuation-in-part of application No. 29/506,114, filed on Oct. 13, 2014, now abandoned.

(57) **CLAIM**

The ornamental design for a handle for medical delivery apparatus device, as shown and described.

DESCRIPTION

FIG. 1 is a three-quarter front isometric view of a first embodiment of a handle for medical delivery apparatus device, showing our new design in a first position;

FIG. 2 is a three-quarter rear isometric view of the handle for medical delivery apparatus device shown in FIG. 1;

FIG. 3 is a rear view of the handle for medical delivery apparatus device shown in FIG. 1;

FIG. 4 is a front view of the handle for medical delivery apparatus device shown in FIG. 1;

FIG. 5 is a right side view of the handle for medical delivery apparatus device shown in FIG. 1;

FIG. 6 is a left side view of the handle for medical delivery apparatus device shown in FIG. 1;

FIG. 7 is a top view of the handle for medical delivery apparatus device shown in FIG. 1;

FIG. 8 is a bottom view of the handle for medical delivery apparatus device shown in FIG. 1;

FIG. 9 is a three-quarter front isometric view of a second embodiment of a handle for medical delivery apparatus device, shown in a first position;

FIG. 10 is a three-quarter rear isometric view of the handle for medical delivery apparatus device shown in FIG. 9;

FIG. 11 is a rear view of the handle for medical delivery apparatus device shown in FIG. 9;

FIG. 12 is a front view of the handle for medical delivery apparatus device shown in FIG. 9;

FIG. 13 is a right side view of the handle for medical delivery apparatus device shown in FIG. 9;

FIG. 14 is a left side view of the handle for medical delivery apparatus device shown in FIG. 9;

FIG. 15 is a top view of the handle for medical delivery apparatus device shown in FIG. 9;

FIG. 16 is a bottom of the handle for medical delivery apparatus device shown in FIG. 9;

FIG. 17 is a three-quarter front isometric view of a third embodiment of a handle for medical delivery apparatus device, shown in a first position;

FIG. 18 is another three-quarter front isometric view of the handle for medical delivery apparatus device shown in FIG. 17;

FIG. 19 is a partially enlarged view of the portion of the handle for medical delivery apparatus device of FIG. 17 delineated by the broken line rectangle shown in FIG. 18; FIG. 20 is a three-quarter rear isometric view of the handle for medical delivery apparatus device shown in FIG. 17; FIG. 21 is a rear view of the handle for medical delivery apparatus device shown in FIG. 17;

FIG. 22 is a front view of the handle for medical delivery apparatus device shown in FIG. 17;

FIG. 23 is a right side view of the handle for medical delivery apparatus device shown in FIG. 17;

FIG. 24 is a left side view of the handle for medical delivery apparatus device shown in FIG. 17;

FIG. 25 is a top view of the handle for medical delivery apparatus device shown in FIG. 17; and

FIG. 26 is a bottom view of the handle for medical delivery apparatus device shown in FIG. 17.

FIG. 27 is a three-quarter front isometric view of the first embodiment of a handle for medical delivery apparatus device shown in a retracted position;

FIG. 28 is a three-quarter rear isometric view of the handle for medical delivery apparatus device shown in FIG. 27;

FIG. 29 is a rear view of the handle for medical delivery apparatus device shown in FIG. 27;

FIG. 30 is a front view of the handle for medical delivery apparatus device shown in FIG. 27;

FIG. 31 is a right side view of the handle for medical delivery apparatus device shown in FIG. 27;

FIG. 32 is a left side view of the handle for medical delivery apparatus device shown in FIG. 27;

FIG. 33 is a top view of the handle for medical delivery apparatus device shown in FIG. 27;

FIG. 34 is a bottom view of the handle for medical delivery apparatus device shown in FIG. 27;

FIG. 35 is a three-quarter front isometric view of the second embodiment of a handle for medical delivery apparatus device shown in a retracted position;

FIG. 36 is a three-quarter rear isometric view of the handle for medical delivery apparatus device shown in FIG. 35;

FIG. 37 is a rear view of the handle for medical delivery apparatus device shown in FIG. 35;

FIG. 38 is a front view of the handle for medical delivery apparatus device shown in FIG. 35;

FIG. 39 is a right side view of the handle for medical delivery apparatus device shown in FIG. 35;

FIG. 40 is a left side view of the handle for medical delivery apparatus device shown in FIG. 35;

FIG. 41 is a top view of the handle for medical delivery apparatus device shown in FIG. 35;

FIG. 42 is a bottom view of the handle for medical delivery apparatus device shown in FIG. 35;

FIG. 43 is a three-quarter front isometric view of the third embodiment of a handle for medical delivery apparatus device shown in a retracted position;

FIG. 44 is a three-quarter rear isometric view of handle for medical delivery apparatus device shown in FIG. 43;

FIG. 45 is a rear view of the handle for medical delivery apparatus device shown in FIG. 43;

FIG. 46 is a front view of the handle for medical delivery apparatus device shown in FIG. 43;

FIG. 47 is a right side view of the handle for medical delivery apparatus device shown in FIG. 43;

FIG. 48 is a left side view of the handle for medical delivery apparatus device shown in FIG. 43;

FIG. 49 is a top view of the handle for medical delivery apparatus device shown in FIG. 43; and,

FIG. 50 is a bottom view of the handle for medical delivery apparatus device shown in FIG. 43.

The broken lines in FIGS. 18 and 19 are used to identify the portion of the partially enlarged view, are for reference purposes only, and form no part of the claimed design.
